UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,032,948.

Specification of Letters Patent. Patented July 16, 1912.

Application filed July 25, 1910. Serial No. 573,628.

To all whom it may concern:

Be it known that I, ARTHUR L. RUSSELL, a citizen of the United States, residing at Hyde Park, in the county of Norfolk and State of Massachusetts, have invented certain Improvements in Lasting-Machines, of which the following description, in connection with the accompanying drawings, is a specification, like reference characters on the drawings indicating like parts in the several figures.

This invention relates to lasting machines of the type which work an upper over the toe portion of a last by wiper plates which are shaped to embrace the end portion of the last and are closed and advanced to wipe the upper inwardly from the end and opposite sides of the toe over the margin of the innersole on the last bottom. In such machines the wipers are required to do more or less stretching or pulling of the upper to shape it to the toe portion of the last and form it to the last without wrinkling any portion of the upper that will show in the finished shoe. Shoes are prepared for the lasting machine by the pulling-over operation in which the upper is seized at the middle of the toe and at the sides of the ball, stretched lengthwise of the shoe, and also transversely of the shoe over the ball of the last, and is adjusted into proper relation to the last. In this preparatory operation the toe tip seam, with which most shoes are now made, is adjusted into a desired relation to the last before the upper is fastened. It is important that this position of the tip seam be not disturbed during the lasting operation. It is the custom of many lasting machine operators to obtain more effective stretching of the upper about the toe portion of the last by gripping or clamping the upper down upon the top face of the wiper plates by means of a device called a retarder. This device retards or delays the slipping of the upper over the wipers as the latter and the last are moved relatively and increases the upper-pulling action of the wiper plates. Many machines have been equipped with retarders, while in other instances retarders are employed which are

disconnected from the machine and held in the hand of the operator. A difficulty is, however, frequently experienced in the employment of these retarders because in their use the upper is often pulled so much that the tip seam is drawn forwardly over the top of the last and curved or "bowed". This occurs because of the need the operator finds for strongly pulling the upper at the sides of the toe in order to fit it smoothly to the last and the fact that the upper has already been strongly pulled at the middle of the toe in the pulling-over operation and cannot be pulled much more without drawing the middle portion of the tip seam forwardly.

An object of this invention is to provide improved lasting means by which bowing of tip seams is avoided and the fitting of the upper to the sides of the toe is facilitated.

To this end important features of this invention consist in the provision of a retarder having an acting face which will grip or clamp the upper against the wiper plates or associated parts with greater force at the sides of the toe than at the end of the toe, and in the combination of a retarder and a subjacent upper clamping or gripping member which are formed relatively to engage and pull the upper at the end and opposite sides of the toe of the shoe and to a greater extent at the sides than at the end of the toe.

The invention will more fully appear from the following description of a preferred embodiment thereof and will be definitely pointed out in the claims at the end of the description.

Figure 1 is a perspective view showing, by way of example, lasting means embodying this invention and comprising a retarder and toe lasting plates operatively connected for co-operative use. Fig. 2 is an edge view of the retarder and plate of Fig. 1. Fig. 3 is an edge view showing a modification. Fig. 4 is a longitudinal section.

The lasting means comprises toe lasting mechanism which may be essentially like that shown and fully described in United States Letters Patent No. 521,954, granted June 26, 1894, on application of Edward

E. Grandy. In this mechanism the wiper plates 2 are supported for movement with their carrier 4 perpendicularly to the plane of the last bottom and are jointed together 5 and mounted for movement backwardly and inwardly over the last bottom. The retarder comprises a carrier bar 10 having a slotted fulcrum connection with a pin 12 on the wiper carrier 4 and adapted to be turned 10 from an out of the way position into a working position over the shoe. The bar 10 is formed for operation, as by a handle at its free end, and has a depending stem upon which are pivoted two wing plates 14 which 15 are curved and relatively movable to adapt them approximately to the contour of the shoe being lasted. A friction washer 15 prevents loose movement of the wings while allowing them to move with the pivoted wiper 20 plates when the latter close over the last. The lower, upper engaging or acting face of the wing plates or retarder proper is formed, as shown in Figs. 2 and 3, out of parallelism with the coöperating upper face 25 of the wiper plates and so that the upper will be gripped with greater pressure at the sides of the toe than at the end of the toe.

In Fig. 2 the acting face of the retarder 30 is slightly concaved over the toe end of the shoe while in Fig. 3 the wiper plates are similarly formed to lessen the clamping pressure applied to the middle portion of the upper relatively to that at the sides of 35 the toe. Obviously both the upper and lower plates may be concaved and also the formation may be such as altogether to avoid gripping the upper at the middle of the toe and grip it only at the sides where bowing 40 of the tip seam is unlikely to result. Also the retarder might grip the upper against some other part than the wiper, as, for example, the wiper holder or a special plate. By the use of this invention the upper may 45 be pulled as much as may be desired or necessary at the sides of the toe for fitting it to the last and working it into smooth lasted position about the more pronounced curves of this portion of the last without 50 liability of pulling upon the middle portion of the upper to an extent to cause bowing of the tip seam. The pivotal connection of the wing plates of the retarder not only enables them to follow the wipers in their closing movement but permits the area of reduced pressure on the middle of the toe of the upper to be widened or narrowed according to the wide or narrow style of toe being lasted. The bar 10 also supports the 55 hold down 20 for engaging the feather edge of the innersole at the end of the toe to hold the edge of the innersole from being lifted by the upwardly stretching upper. The hold down is connected to a lever 22

which is fulcrumed on a block which is adjustable on the bar 10 and has its handle end adapted to be embraced by the fingers of the operator for moving the other end to impel the hold down downwardly upon the shoe at the will of the workman. A spring 70 24 serves to maintain the hold down normally upright where it permits the retarder to be used as freely as if the hold down were not present. It is contemplated that the hold down will be depressed only 75 when the operator observes that the edge of the innersole is being or is liable to be lifted by the stretching upper that is being pulled up by the wipers and the retarder. This is particularly liable to occur when the innersole is large and overhangs the edge of the last a trifle. It is to be noted that the inclination of the hold down and of its path of movement permits its withdrawal from under the upper after the upper has been 80 wiped over the edge of the innersole past the position where the feather is liable to be displaced by it. As I am advised it is new with me to provide in connection with an end lasting mechanism a feather hold down 85 mounted on a support where it is in position to be thrust into holding relation to the innersole whenever required.

Having described my invention, what I claim as new and desire to secure by Letters 90 Patent is:—

1. An apparatus of the class described, having in combination, wiper plates, and a retarder for engaging an upper at the end and opposite sides of the toe of a last the coöperating upper-clamping faces of which are relatively formed to hold the upper more firmly between them at the sides of the toe than at the end of the toe. 100

2. An apparatus of the class described, having in combination, means for engaging an upper at the end and opposite sides of the toe of a last comprising coöperating members having substantially continuous crescent-shaped upper engaging faces which are 110 constructed and arranged to seize the upper more firmly at the sides than at the end of the toe, and means for relatively actuating said members and the last to pull the upper. 105

3. An apparatus of the class described, having in combination, wiper plates and a retarder comprising pivotally connected wings 14 recessed on their lower faces to reduce holding pressure on the upper at the middle of the toe and relatively movable 120 pivotally to vary the width of reduced pressure according to the broad or narrow shape of the toe end of the last. 115

4. A retarder for use in lasting comprising a plate shaped to clamp an upper upon 125 toe lasting plates and formed with a shallow recess in its lower face over the middle of the toe portion of the upper.

5. A retarder for use in lasting shaped and arranged throughout its length to position the upper flat down in a plane substantially parallel with the shoe bottom and having an upper clamping face formed to hold the upper less firmly at the end of the toe than at the sides of the toe of the shoe. 67
6. A retarder for bed lasting machines comprising a bar extending lengthwise of a shoe which occupies position to be lasted in the machine and pivotally supported in front of the shoe and having a handle on its rear end, said bar having a depending foot adapted to be held in clamping engagement 10 with the marginal portion of the upper upon the lasting plates by pressure applied to the handle transversely of the length of the handle and being recessed in its lower face over the middle of the toe for the purpose 15 described. 20
7. A retarder comprising two plates pivotally connected together over the middle of the toe for adjustment according to different widths of shoes and each recessed on its lower face at and adjacent to said connection to reduce upper gripping pressure at the middle of the toe over a width varying with the width of shoe for which the plates are pivotally adjusted. 25
8. A retarder comprising a lever pivoted at one end and having a handle at its other end, and an upper clamping member mounted on the lever and having its lower face formed to clamp the upper at the end and 30 sides of the toe and to hold the upper at the sides with greater security than at the end of the toe. 35
9. In an end lasting mechanism the combination with end embracing wipers and 40 means for advancing and closing them, of an innersole edge hold down, mounted relatively to said wipers to stand normally over the shoe ready for use, and means for actuating the hold down into engagement with the feather of the innersole to hold the feather while the wipers advance over it, and a spring to retract the feather holder automatically from the path of the wipers when permitted to do so. 45
10. In an end lasting mechanism the combination with end embracing wipers and a retarder having an operating handle fulcrumed in front of the wipers and extending rearwardly over the shoe, of an innersole 50 edge hold down mounted on the retarder. 55
11. In an end lasting mechanism the combination with end embracing wipers and a retarder having an operating handle extending rearwardly over the shoe, of an innersole edge hold down movably mounted on the retarder and adapted to be brought into use at the will of the operator. 60
12. In an end lasting mechanism a retarder and an innersole edge hold down 55
- mounted on the retarder and formed and arranged to extend forwardly across the lip or shoulder of a welt shoe innersole into engagement with the feather of the innersole, means for maintaining the hold down normally in a raised and rearwardly displaced position relatively to the retarder and means for depressing and advancing the hold down relatively to the retarder. 65
13. In an end lasting mechanism a retarder and an innersole edge hold down 70 yieldingly upheld on the retarder and means for moving it downwardly and forwardly to operative position. 75
14. In an end lasting mechanism the combination with end embracing wipers and 80 means for actuating them manually, of an innersole edge hold down and supporting and guiding means in which the hold down is mounted for movement in an oblique path inclined upwardly and backwardly to facilitate its withdrawal from under a partially overworked upper in time relation to the movement of the wipers. 85
15. In an end lasting mechanism, a carrier mounted for movement over the shoe 90 and a hold down mounted in the carrier for movement downwardly and forwardly. 95
16. In an end lasting mechanism the combination with end embracing wipers and supporting and operating means therefor, of a retarder mounted for movement lengthwise of the shoe with the wipers and an innersole tip hold down mounted on the retarder and arranged for downward and forward movement relatively to the retarder. 100
17. An apparatus of the class described having, in combination, toe lasting wipers, a retarder between which and the wipers the upper of the end and sides of the toe is received, said wiper and retarder being relatively recessed in their adjacent faces between which the upper of the end of the toe is received whereby the end of the upper is held less firmly than is the upper at the sides of the toe. 105
18. An end lasting machine having, in combination, toe embracing wipers and means for operating them, and a retarder comprising a manually operable lever to which is attached a crescent-shaped foot 110 having its horns extending toward the rear of the shoe and away from the fulcrum of the lever and arranged to permit pressure applied to the lever to retard slipping of the upper more at the sides than at the end of the toe, the acting face of the body of said foot being cut away to relieve the pressure at the end of the shoe while maintaining the pressure at the sides of the shoe. 115
19. An end lasting machine having, in combination, toe embracing wipers and means for operating them, and a retarder comprising a manually operable lever to 120
- 125

which is attached a crescent-shaped foot, having its horns extending toward the rear of the shoe and away from the fulcrum of the lever and arranged to permit pressure applied to the lever to retard slipping of the upper more at the sides than at the end of the toe, a hold down which is mounted upon the retarder lever for movement therewith and which is yieldingly held in inoper-

ative position, and means to move the hold down into operative position.

In testimony whereof I have signed my name to this specification in the presence of two subscribing witnesses.

ARTHUR L. RUSSELL.
